Primary Examiner — Derrick Holland*Assistant Examiner* — Lauren Calve(74) Attorney, Agent, or Firm — QuickPatents; Kevin Prince(57) CLAIM

I claim the ornamental design for a personalized weekly garment marker, as shown and described.

DESCRIPTION

FIG. 1 is a perspective view of a personalized weekly garment marker, showing my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines showing of a personalized weekly garment marker represents unclaimed subject matter and forms no part of the claimed design.
